UNITED STATES PATENT OFFICE.

FISHER H. LIPPINCOTT, OF PHILADELPHIA, PENNSYLVANIA, ASSIGNOR TO
LIPPINCOTT PENCIL COMPANY, OF PHILADELPHIA, PENNSYLVANIA, A
CORPORATION OF PENNSYLVANIA.

PENCIL.

No. 851,893.

Specification of Letters Patent.

Patented April 30, 1907.

Application filed November 27, 1906. Serial No. 345,274.

To all whom it may concern:

Be it known that I, FISHER H. LIPPINCOTT, a citizen of the United States, residing at Philadelphia, in the county of Philadelphia and State of Pennsylvania, have invented certain new and useful Improvements in Pencils, of which the following is a specification.

This invention relates to improvements in pencils containing lead, crayon, erasing rubber and the like, and pertains particularly to a pencil of the general type shown in my Patent No. 613,452, in which a lead or other insert is disposed within a holder and is normally held against rearward movement therein.

15 The invention aims as a primary object thereof to provide, in a device of the type mentioned, novel and improved means for feeding the insert forward in the holder, for preventing accidental rearward movement thereof and for permitting of the rearward movement of the insert when such movement is desired.

25 The construction of my invention will appear from the following description, in which reference is had to the accompanying drawings forming a part of this specification, like numerals designating corresponding parts throughout the several views, wherein,

30 Figure 1 is a side elevation of a pencil constructed in accordance with my invention. Fig. 2 is a central longitudinal section thereof the holder being shown as containing a lead insert. Fig. 3 is a central longitudinal section taken at right angles to Fig. 2. Figs. 4 and 5 are fragmentary longitudinal sections at right angles to one another of a modified embodiment of the invention, and Fig. 6 is a central longitudinal section of a further modified embodiment, showing the use of a 35 crayon or erasing rubber insert.

In the forms of my invention illustrated, I employ a cylindrical holder 1 preferably of wood which is formed with a longitudinal bore 2 extending therethrough and with a 45 narrow longitudinal slot 3 communicating with said bore. The slot 3 preferably terminates short of the forward end 4 of the pencil in order that the latter may be made solid or it may be reinforced if desired, to 50 prevent bending or collapsing under the strain of use and to prevent the insert drop-

ping out in case the latter breaks within the holder 1. Within the bore 2 is a cylindrical insert 5 which may be of any desired material in accordance with the particular use for 55 which the article is intended, Figs. 2 to 5 illustrating an insert of lead and Fig. 6 an insert of greater diameter, such as crayon or erasing material. In order that the insert 5 may be held against transverse movement 6c in use, and to prevent any lateral movement or "play" thereof, a suitably constructed sleeve 6 is fitted within the outer end of the bore 2, and forms the inner wall of the pointed end 4. This sleeve 6 may be of any form 65 or material suited to accomplish the purposes mentioned and may be slotted if desired.

Novel means are provided for locating and holding the insert 5 in any desired position in the bore 2. This means comprises a 70 holder or follower constructed of wire in the preferred embodiment of the invention and comprises a projection or finger piece which extends through the slot 3, and a rearwardly extending arm having a sharpened extremity 75 designed to engage the walls of the bore to prevent accidental or undesired rearward movement of the insert. The wire is bent upon itself, as shown, to form the projection or finger piece 7. Adjacent this finger piece 8c and preferably integral therewith is a sleeve 8 formed by bending the wire into a spiral which is proportioned and arranged to grasp the insert 5 received therein in a strong frictional engagement. The finger piece 7 is 85 provided with a curved arm 9, the rearward extremity of which is preferably flattened and sharpened to form a biting edge 10 for frictional engagement with the sides of the bore to prevent accidental forward movement 90 of the insert 5, and by penetrating the walls of the bore when the insert is pressed rearwardly to prevent rearward movement thereof. The arm 9 thus serves the function of a locking dog and in such use is capable of being variously modified from the construction above described. Figs. 4 and 5 illustrate for example an advantageous modification in which the arm 9 is bent at a slight angle to the plane of the finger piece so 100 that its pointed extremity will contact at all times with the surface of the bore.

In the modified embodiment of the invention illustrated in Fig. 6 the follower is constructed of sheet metal stock. The holder 1 is provided along a line diametrically opposite the slot 3, with a longitudinal groove or recess 11 and portions of the follower project into the slot 3 and the groove or recess 11 as guides. The insert 5 is frictionally gripped by integral forwardly extending jaws 12 which are employed in lieu of the spiral sleeve 8. The arm 9 consists of an integral resilient rearward extension of the finger piece 7 and may be formed with a flattened or pointed extremity as already described. A cap plate closes the rearward end of the bore 2 and surrounds the holder 1. The plate may be formed to hold an eraser, pencil sharpener or the like if desired.

While the sleeve 8 is primarily designed to frictionally engage the insert and to hold the same, it may also be so proportioned to exert some degree of pressure upon the surrounding surface of the bore 2 in order that the insert will not move forward except when pressure is applied to the finger piece or projection 7. Should the insert be moved forward to too great an extent, it may be moved rearwardly by depressing the finger piece or projection 7, so as to move the projection 9 out of engagement with the wall of the bore 2 and to thus permit of the free rearward movement of the follower until the finger piece is released.

While I have shown and described preferred forms of my present invention, it is to be understood that it is not limited to the precise forms shown, but contemplates broadly any construction within the scope of the appended claims.

Having fully described my invention, I claim:

1. In a device of the character described, an elongated holder provided with a longitudinal bore, a follower in said bore, having an arm provided with a rearwardly extending sharpened portion normally spring pressed against the wall of the bore and means associated with said arm for positively moving said arm out of engagement with said wall.

2. In a device of the character described, an elongated holder having a longitudinal bore and a slot extending through the side of said holder and communicating with said bore, a follower in said bore, a spring arm carried by said follower having a sharpened extremity normally engaging the wall of said bore, and means associated with said arm and extending through said slot for moving said spring arm against the tension thereof out of engagement with said wall.

3. In a device of the character described, an elongated holder provided with a longitudinal bore and a slot extending through the side of said holder and communicating with said bore, a follower in said bore adapted to

grasp a lead or other insert, a projection carried by said follower and extending through said slot and an arm normally spring pressed against the wall of the bore to prevent rearward movement of the said follower, said arm being adapted to be thrown out of engagement with the said wall by manipulation of the said projection, whereby said follower may be moved rearwardly in said bore.

4. In a device of the character described, an elongated holder provided with a longitudinal bore extending therethrough and a slot extending through the side of said holder and communicating with said bore, a follower in said bore adapted to grasp a lead or other insert, a finger piece or projection carried by said follower extending through said slot and a rearwardly extending arm having a sharpened extremity normally spring pressed against the wall of the bore to prevent rearward movement of the said follower, said arm being adapted to be thrown out of engagement with said wall by manipulation of the said finger piece or projection, whereby said follower may be moved rearwardly in said bore.

5. In a device of the character described, an elongated holder provided with a longitudinal bore extending therethrough and a slot extending through the side of said holder and communicating with said bore, and a follower in said bore comprising an integral section of wire, one end of which is bent into the form of a socket or sleeve to grasp the lead or other insert, and the other end thereof sharpened and normally pressed against the side of the bore to prevent rearward movement of said holder or follower.

6. In a device of the character described, an elongated holder provided with a longitudinal bore extending therethrough and a slot extending through the side of said holder and communicating with said bore, and a follower adapted to grasp a lead or other insert, said follower comprising a section of wire having a portion at one end thereof bent into the form of a socket or sleeve to engage the said insert, and the opposite end having the form of an arm provided with a sharpened extremity, said arm being normally pressed against the side of said bore to prevent rearward movement of the follower, an intermediate portion of said wire being bent upon itself to form a projection which extends through the said slot, whereby the said follower may be manipulated.

7. In a device of the character described, an elongated holder provided with a longitudinal bore and a slot extending through the side of said holder and communicating with said bore, and a follower located in said bore and adapted to grasp a lead or other insert, said follower comprising an integral section of wire having a portion at one end thereof bent into the form of a socket or sleeve to

hold the said insert and the opposite end bent into the form of an arm having a sharpened extremity, said arm being normally spring pressed against the side of the bore, and means extending through said slot adapted to throw said arm out of engagement with said wall.

In testimony whereof I affix my signature in presence of two witnesses.

FISHER H. LIPPINCOTT.
